ELECTRON DISCHARGE DEVICE

Polykarp Kusch, Bloomfield, N. J., assignor to
Westinghouse Electric Corporation, East Pittsburgh, Pa., a corporation of Pennsylvania

Application August 20, 1941, Serial No. 407,539

12 Claims. (Cl. 250—27.5)

1

The present invention relates, generally, to electron discharge devices, and has reference, in particular, to production of ultra high frequency oscillations.

Tuned resonators have heretofore been employed, separated by a field-free space, and cooperating to first bunch the electrons and then catch them at an advantageous moment when power may be derived therefrom. The usual construction of devices of this sort are affected with adverse space charge due largely to severe concentration of electrons in transit, and which inter alia, interferes with bunching at a sharply defined position.

The present invention seeks to remedy deficiencies in the prior art constructions, especially those aforementioned, wherefore, it may be said that an object of the present invention is to generally improve operation and efficiency of a resonant type electron discharge device.

A further object of the present invention is to concentrate the electrons at a sharply defined bunched position, but in their transit to such position to keep them spread laterally from each other, and accordingly, to reduce space charge effects.

Another object of the present invention is to obtain a density modulation while maintaining constant velocity of electrons.

Still further objects will appear to those skilled in the art as the description progresses, both by direct statement thereof and by implication from the context.

In the accompanying drawing, wherein like numerals of reference indicate similar parts throughout the several views;

Figure 1 is a side-edge view of an electron discharge device in accordance with my invention; and

Figure 2 is a sectional view thereof on line II—II.

In the specific embodiment of the invention illustrated in said drawing, two hollow-body resonators 10, 11, of substantially doughnut or toroidal shape are shown, arranged so that the central planes of each are perpendicular to each other. For convenience in description and relative location, the first of these resonators, commonly known as the buncher, and here designated by numeral 10, will be considered as standing upright on edge, whereas the other one, 11, generally designated the catcher, will be considered as resting flatwise or horizontally. The central axis of developed revolution of the first resonator or buncher 10 lies in the extended

2

central plane of the second resonator or catcher 11, said axis and plane being indicated by the dot-dash line 12. The mid-portions of each resonator provide attenuated walls as common with this type of resonator. In the instance of the catcher 11, the attenuated walls constitute perforate grids 13, 14, the distance between which is tunable in well known manner (not shown) by changing the relative spacing of said grids from each other.

The two resonators 10, 11 are shown physically separated one from the other and joined by a crescent-like conduit 15 which emanates from a top part of the toroidal wall of the buncher 10 and merges with the catcher 11 around the upper grid 13. At the juncture of the buncher 10 and the crescent-like conduit 15, is provided an upper grid 16 to maintain the general hollow-body resonant characteristic of the resonator. At the bottom of the first resonator, diametrically opposite from said upper grid 16 thereof, is a lower grid 17.

A re-entrant stem-tube structure or envelope 18 of glass or other suitable insulative material is shown sealed to the under portion of the first resonator or buncher below said lower grid 17. In said envelope is a cathode 19, here shown as indirectly heated by filamentary heater 20 and source of current 21, said cathode having an emitting surface parallel to and below grid 17 and adapted to produce a copious flow of electrons. Said grid 17 is made positive to the cathode, as by battery 22 and suitable connections between grid and cathode, thereby accelerating the electrons upwardly and diametrically of the resonator to pass into the crescent-like conduit 15. Resonance of buncher 10, augmented by a feed-back of oscillating energy from the second resonator or catcher by interconnected coupling loops 23, 24, produces an electric field oscillating between the solid attenuated walls 25 of the said buncher 10. This oscillation affects the electron beam, introducing a small lateral component of velocity tending to swing the beam back and forth laterally. However, since this lateral component is exceedingly small compared to the forward velocity, it may be said that the resultant forward velocity remains substantially the same.

Associated with the crescent-like conduit and resonators, is means for establishing and maintaining a constant magnetic field. An electromagnet M is shown for the purpose with its pole-pieces P, P' at opposite sides of the crescent-like conduit for maintaining a constant

field. The direction of that field is inward toward the paper in Fig. 2, or from left to right in Fig. 1. Such a field tends to cause electrons to adopt an arcuate path clockwise to the field direction. The intensity of the field is maintained constant both in terms of time and area of pole piece, thereby obtaining constant radius of curvature of the arcuate path described by an electron. The field intensity and shape of the crescent-like conduit are proportioned and arranged so that an electron not otherwise deflected will describe a semi-circle through the middle of the crescent from end to end thereof from a midpoint A in the buncher 10 to a midpoint B in the catcher 11. It may now be said that any other electron having the same forward velocity and leaving point A will pass to point B, points A and B being situated on aforementioned plane 12. This is true of electrons to which a lateral component is given by field impulse of the buncher, whether that lateral component be from right or left. The lateral component, in effect, infinitesimally alters the radius of curvature and shifts the center of curvature up or down depending upon whether the lateral component is in a direction away from or toward the center of curvature. This has been illustrated in greatly exaggerated scale by showing normal path C of an electron A to B, as a true semi-circle of radius r about center of curvature p , and by showing paths D and E for extreme right and left deflected electrons respectively having substantially equal radii r' and r'' of path curvature centered at p' and p'' but describing paths less than and greater than semi-circular normal path C. However, since path D is shorter than normal path C, the time of travel of electrons through path D is less than for electrons traveling on normal path C, and similarly, since path E is longer than normal path C, time of travel of electrons through path E is greater than for electrons traveling on normal path C. Consequently, the modulation impressed by the lateral displacement or swinging of the electron beams at the buncher enables electrons in shorter path D to leave point A later than electrons on normal path C and both arrive at B at the same time, whereas electrons on path E which start sooner than those in normal path C arrive at B at the same time as electrons of the latter path C mentioned. The result, by use of appropriately tuned oscillation, magnetic field, voltage, coupling and other well known functional requirements in design, is a density bunching of electrons in the catcher at point B. Energy may be derived from these bunched electrons, a small portion being fed back by coupling 24 to coupling 23 and the major portion being fed to an output by a suitable coupling 26 in the buncher. The electrons pass through the lower grid of the catcher and expend their remaining energy within and against the walls of a collector 27. It is to be understood that the collector, resonators, crescent-like conduit enclosure and envelope are inter-communicating with each other and are all evacuated.

In operation, it is to be understood that the foregoing description as to the three particular electron beams from the particular point A is duplicated by myriad other electrons passing through the buncher 10, so that the actual beam has a cross-sectional area substantially that of the upper grid 16 of the buncher. The periodic modulation applying a lateral component affects

the whole cross-sectional area of the beam. In view of the enlarged cross-sectional area of the crescent-like conduit, and the deflection or different arcs of flow of the electrons, the said electrons are not crowded together in transit, the desirable consequence of which is substantial elimination of space charge effects and a very decided increase of efficiency over known electron discharge devices of the hollow-body resonator type. It must be remembered that the poles P and P' of magnet M establish and maintain a fixed magnetic field, and that in such a field an electron with a certain velocity will describe an arcuate path of determinable radius which will always be the same under the given conditions. Application of a lateral component of deflection does not introduce a substantial change of radius of curvature since the electron velocity has been only very slightly changed. Thus, only the center of curvature and the length of the arc without any material change of radius, are affected by the introduced lateral component. The transit time accordingly is a function of the lateral displacement of the beam.

Electrons from the cathode are accelerated with potential difference V between cathode and grid. They pass between the attenuated mid-portion or plates 25 of the buncher 10 across which a periodically varying field potential difference $V_d \sin \omega t$ exists, which thereby sways the electron beam back and forth with a periodically varying orientation of the tuned frequency of the resonators. The heretofore described bunching of electrons due to difference in transit time occurs in the catcher, and with bunched electrons passing through the field thereof when the field opposes the motion of the electrons, they will accordingly deliver energy to the field which causes the resonator to oscillate and accomplishes the desired output. The resonators are tuned to the oscillating frequency and the feedback from catcher to buncher is accordingly part of the coupling of the whole as a resonant system.

Since the various details of construction, as well as the precise relation and functioning of parts are subject to variation and change without departing from the inventive concept or scope of the invention, it is intended that all matter contained in the specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

I claim:

1. An electron discharge device comprising a buncher resonator and a catcher resonator at right angles to each other and having mid-points thereof in a common plane, means for producing a beam of electrons through the buncher resonator, electrode means for applying a lateral component of travel periodically on said beam, and means between said buncher and said catcher for establishing a curvature of fixed radius to the path of the electron beam, whereby a density modulation is produced effective at the catcher resonator.
2. An electron discharge device comprising a buncher resonator and a catcher resonator at right angles to each other and having mid-points thereof in a common plane, means for producing

a beam of electrons through the buncher resonator, feed-back means electrically connected from the catcher resonator to the buncher resonator for applying a lateral component of travel periodically on said beam in the buncher resonator, and means between said buncher and said catcher for establishing a curvature of fixed radius to the path of the electron beam, whereby a density modulation is produced effective at the catcher resonator.

3. An electron discharge device comprising a buncher resonator and a catcher resonator at right angles to each other and having mid-points thereof in a common plane, means for producing a beam of electrons through the buncher resonator, electrode means for applying a lateral component of travel periodically on said beam, and means between said buncher and said catcher providing a fixed magnetic field transverse to the electron beam for establishing a curvature of fixed radius to the path of the electron beam, whereby a density modulation is produced effective at the catcher resonator.

4. An electron discharge device comprising a buncher resonator and a catcher resonator at right angles to each other and having mid-points thereof in a common plane, means for producing a beam of electrons through the buncher resonator, feed-back means electrically connected from the catcher resonator to the buncher resonator for applying a lateral component of travel periodically on said beam in the buncher resonator, and means between said buncher and said catcher providing a fixed magnetic field transverse to the electron beam for establishing a curvature of fixed radius to the path of the electron beam, whereby a density modulation is produced effective at the catcher resonator.

5. An electron discharge device comprising a toroidal buncher resonator having attenuated solid walls at its middle portion, a toroidal catcher resonator having attenuated perforate grid walls at its middle portion, said resonators being angularly disposed with respect to each other, electrode means for producing a beam of electrons through the buncher resonator, means between said buncher and said catcher for applying a lateral component of travel periodically on said beam between the attenuated solid walls of the buncher resonator, and means for establishing a curvature of fixed radius to the path of the electron beam from the buncher resonator to the perforate grid middle portion of the catcher resonator whereby a density modulation is produced effective at the catcher resonator.

6. An electron discharge device comprising a toroidal buncher resonator having attenuated solid walls at its middle portion, a toroidal catcher resonator having attenuated perforate grid walls at its middle portion, said resonators being angularly disposed with respect to each other, means between said buncher and said catcher for establishing a curvature of fixed radius to the path of electron beam from the buncher resonator to the perforate grid middle portion of the catcher resonator, and means for varying the length of arcuate path while retaining constant radius of arc of said electron beam, whereby a density modulation is produced effective at the catcher resonator.

7. An electron discharge device comprising a toroidal buncher resonator having attenuated solid side walls at its middle portion, a toroidal catcher resonator having attenuated perforate grid walls at its middle portion, said resonators

having transverse relation one to the other, an extended central axis through the buncher resonator perpendicular to said solid side walls crossing a similar axis of the catcher resonator and lying in a plane midway between and parallel to said perforate grid walls thereof, and means for projecting a modulated electron beam from the buncher resonator to the grid portion of the catcher resonator.

10. An electron discharge device comprising a toroidal buncher resonator having attenuated solid side walls at its middle portion, a toroidal catcher resonator having attenuated perforate grid walls at its middle portion, said resonators having transverse relation one to the other, an extended central axis through the buncher resonator perpendicular to said solid side walls crossing a similar axis of the catcher resonator and lying in a plane midway between and parallel to

15 said perforate grid walls thereof, means for producing a beam of electrons through the buncher resonator between said attenuated side walls thereof, means for establishing a curvature of fixed radius to the path of electron beam from the buncher resonator to the grid middle portion of the catcher resonator, and means for varying the length of arcuate path of said beam, whereby a density modulation is produced effective at the catcher resonator.

20 30 An electron discharge device comprising a toroidal buncher resonator having attenuated solid side walls at its middle portion, a toroidal catcher resonator having attenuated perforate grid walls at its middle portion, said resonators having transverse relation one to the other, an extended central axis through the buncher resonator perpendicular to said solid side walls crossing a similar axis of the catcher resonator and lying in a plane midway between and parallel to

25 said perforate grid walls thereof, means for producing a beam of electrons through the buncher resonator to the grid portion of the catcher resonator, and means for varying the length of arcuate path of said beam, whereby a density modulation is produced effective at the catcher resonator.

35 40 An electron discharge device comprising a toroidal buncher resonator having attenuated solid side walls at its middle portion, a toroidal catcher resonator having attenuated perforate grid walls at its middle portion, said resonators having transverse relation one to the other, an extended central axis through the buncher resonator perpendicular to said solid side walls crossing a similar axis of the catcher resonator and lying in a plane midway between and parallel to

45 said perforate grid walls thereof, means for projecting a modulated electron beam from the buncher resonator to the grid portion of the catcher resonator, and a crescent shaped conduit connecting said resonators for the modulated electron beam.

45 50 An electron discharge device comprising a toroidal buncher resonator having attenuated solid side walls at its middle portion, a toroidal catcher resonator having attenuated perforate grid walls at its middle portion, said resonators having transverse relation one to the other, an extended central axis through the buncher resonator perpendicular to said solid side walls crossing a similar axis of the catcher resonator and lying in a plane midway between and parallel to

55 said perforate grid walls thereof, means for producing a beam of electrons through the buncher resonator between said attenuated side walls thereof, a magnet of fixed field between said resonators for establishing a curvature of fixed radius to the path of electron beam from the buncher resonator to the grid middle portion of the catcher resonator, and means for applying a lateral component of travel on said beam for

60 65 varying the length of arcuate path of said beam, whereby a density modulation is produced effective at the catcher resonator.

65 70 An electron discharge device comprising a buncher resonator and a catcher resonator, electrode means for projecting a beam of electrons from the buncher resonator toward the catcher resonator, means between said buncher and said catcher for rendering the path traversed by said beam varying in length from the buncher resonator to the catcher resonator, and a conduit

75

progressively increasing in cross-sectional area from the buncher resonator to a distant portion therefrom for both admitting of the varying path lengths of the beam and to reduce space charge effects.

12. An electron discharge device comprising a buncher resonator and a catcher resonator, electrode means for projecting a beam of electrons from the buncher resonator on an arcuate path from the buncher resonator toward the catcher resonator, means between said buncher and said catcher for varying the arcuate length of path of said beam, and a crescent-like conduit connecting said resonators together for said beam for both admitting the varying arcuate paths of

the beam and to reduce space charge effects by the electrons following such paths.
